UNITED STATES PATENT OFFICE.

CHARLES D. SYMMS, OF SIOUX FALLS, SOUTH DAKOTA.

SPARK-PLUG CASE.

Application filed June 11, 1921. Serial No. 476,643.

To all whom it may concern:

Be it known that I, CHARLES D. SYMMS, a citizen of the United States, residing at Sioux Falls, in the county of Minnehaha 5 and State of South Dakota, have invented certain new and useful Improvements in Spark-Plug Cases, of which the following is a specification.

My invention relates to spark plug cases 10 and has for one of its objects the provision of a simple and efficient device of this character adapted to hold spark plugs in a manner to prevent their accidental injury, even if the case is put in a tool-box 15 with tools, or thrown loosely in a portion of a vehicle, or the like.

A further object is the provision of a spark plug case of substantially rigid material having a resilient clamping member 20 within the casing for holding the spark plug against movement.

Other objects will appear hereinafter.

An embodiment of my invention is illustrated in the accompanying drawing, forming 25 a part of this specification, and in which—

Fig. 1 is a side view of a casing embodying my invention and showing a portion broken away to expose underlying parts;

Fig. 2 is a section taken on line 2—2 of Fig. 1;

Fig. 3 is a section of the case taken on line 3—3 of Fig. 1 and showing a spark plug therein in elevation; and

Fig. 4 is a view, in perspective, of a clamping jaw used in the construction.

Referring more particularly to the drawing, I have indicated a housing made up of a box 5 and a cover 6 telescoped over the 40 box. It will be apparent that the housing may be arranged in any desirable manner and of a size to accommodate different numbers of spark plugs than that illustrated. I have indicated the housing formed to accommodate four spark plugs as an example. The box and cover may be formed of sheet metal, such as commercial tin plate, or any other desirable substance.

Within the box 5 I have indicated two 50 clamping jaws 7 which are substantially alike. These jaws 7 may be formed of the same material as the box and cover or a material having more resiliency, when desired. The clamping jaws 7 are preferably loosely mounted in the box 5 and of such

shape that they will be held in position by friction and their resiliency.

In the form shown each of the jaws 7 has substantially semi-cylindrical portions 8, and these semi-cylindrical portions 8 joined by somewhat acute angular portions 9. These parts 8 and 9 are preferably formed so that when the jaws are inserted in the box the distance between the middles of the parts 8 will be slightly more than the distance between two points 9 so that the portion 10 of the spark plug will tend to straighten out the parts 8 and thereby frictionally lock the plugs in position in the box. When the cover 6 is removed this 10 frictional contact between the plugs and the jaws 7 will hold the plugs in the box, even though the latter is inverted or laid down.

The height of the jaws 7 is preferably such that their upper edges will engage 75 against some part of the plugs, such as shoulders 11, and prevent movement of the plug downwardly, thereby holding the electrodes 12 in such positions that they cannot engage the bottom of the box or the jaws 7. This insures keeping the plugs in perfect condition. The upper end 13 of the plug is adapted to be engaged by the inner wall of the top of the cover so as to hold the plug tightly against the top of the clamp 7, thereby holding the plugs against longitudinal movements in the box. It will be apparent that the cover in its condition shown in Fig. 1 will accommodate spark 85 plugs of different lengths by telescoping greater or less distances over the box 5.

I claim:—

1. A spark plug case comprising a housing of substantially rigid material, and means within said housing for resiliently 95 gripping a spark plug and for supporting said plug with one end thereof free from contact with said housing.

2. A spark plug case comprising a housing, and means within said housing for resiliently gripping a spark plug, said means having resilient gripping jaws for engaging opposite portions of a spark plug and providing a supporting shoulder for maintaining said plug in position with one end thereof free from contact with said housing.

3. A spark plug case comprising a housing having a strip of resilient sheet material therein bent to form jaws for engaging opposite sides of a spark plug, said strip be- 110

- ing free from fixed attachment to said housing to permit said jaws to conform in position to plugs within said case and to resiliently grip said plugs.
5. A spark plug case comprising a housing having sheet metal positioning means therein for retaining spark plugs in place in said housing, said positioning means comprising strips of sheet material bent to form 10 arcs, the strips being arranged adjacent one another with their arcs in complementary position to provide a series of substantially circular openings with the strips arranged one on each side of said openings.
15. A spark plug case comprising a housing and a pair of positioning strips arranged within said housing and free from fixed attachment therewith, said strips being bent to form a series of arcs and being positioned 20 within said housing so that the arcs of one strip register with the arcs of another strip and constitute substantially cylindrical sockets for receiving plugs.
25. A spark plug case comprising a housing and clamping means within said housing, said means comprising a pair of resilient strips of sheet metal bent to form a series of arcs, said strips being arranged adjacent one another with the arcs thereof 30 registering to provide substantially cylindrical sockets so that the adjacent portions of the strips constitute spring jaws for clamping opposite portions of plugs within said sockets while the edges of said strips 35 provide shoulders for sustaining the plugs with one end thereof spaced from the wall of said housing.
7. A spark plug case comprising telescoping sections, clamping strips within one of 40 said sections, said strips being bent to provide registering portions forming sockets for receiving the ends of spark plugs, the edges of said strips providing shoulders for
- supporting the ends of the plugs within said sockets in spaced relation to the bottom of 45 said sockets while the other telescoping member is free to engage the opposite ends of said spark plugs.
8. A spark plug case comprising a housing, a pair of strips of resilient sheet material disposed adjacent one another within 50 said housing to provide frictional gripping members, said strips being bent to form registering gripping jaws for entering the space between plugs in said housing from opposite sides, the space between adjacent jaws 55 of a single strip being normally less than the greatest distance from one of said strips to the other across said housing to cause said jaws to resiliently engage said plugs to retain them in position in said housing.
9. A spark plug case comprising a pair of telescoping box sections forming a relatively thin elongated housing, and a pair of strips of resilient sheet material disposed in one 60 of said sections and bent to provide registering portions forming a series of sockets for receiving spark plugs, said strips being free from fixed attachment with said housing to permit the side walls of said sockets to 65 resiliently accommodate themselves on plugs inserted in said sockets so that said walls will grip said plugs, the adjacent strips forming opposite portions of said sockets while the edges of said strips provide shoulders for restricting the movement of the 70 plugs into said sockets to maintain the inner ends of said plugs free from contact with the bottoms of said sockets while the opposite ends of said plugs are free to engage the wall 75 of the other telescoping member.
- In testimony whereof I have signed my name to this specification on this 6th day of June, A. D. 1921.

CHARLES D. SYMMS.
